UNITED STATES PATENT OFFICE.

RICHARD W. UHLIG, OF ARLINGTON, NEW JERSEY, ASSIGNOR TO ALLEN TYPEWRITER COMPANY, OF ALLENTOWN, PENNSYLVANIA, A CORPORATION OF PENNSYLVANIA.

TYPEWRITING MACHINE.

1,412,637.

Specification of Letters Patent. Patented Apr. 11, 1922.

Application filed June 20, 1917, Serial No. 175,829. Renewed September 9, 1921. Serial No. 499,543.

To all whom it may concern:

Be it known that I, RICHARD W. UHLIG, a citizen of the United States, and a resident of Arlington, in the county of Essex and State of New Jersey, have invented certain new and useful Improvements in Typewriting Machines, of which the following is a specification.

This invention relates to typewriting machines and particularly to typewriting machines in which the type strike rearwardly against the front of a platen, the platen being rotatably carried by a carriage which is shiftable upward and downward to support the carriage with the writing line of the platen which is in a plane in line with the axis of the platen in different planes, and it is the object of the invention to provide improved means to support the platen carriage in the normal writing position and to shift said carriage above the normal writing position and releasably lock it in such position.

It is another object of the invention to provide improved carriage shifting means to shift the carriage above or below the normal writing position and to releasably lock it in either of such positions.

In the drawings accompanying and forming a part of this specification Figure 1 is a sectional side elevation of a typewriting machine illustrating an embodiment of my invention with the parts in position to support the platen in normal writing position, only such parts of the typewriting machine being shown as are essential to an understanding of the invention.

Figure 2 is a view similar to Figure 1 but showing the parts in position with the carriage shifted upward with the platen above the normal writing position.

Figure 3 is a view similar to Figure 1 but showing the parts in position with the carriage shifted downward with the platen below the normal writing position.

Figure 4 is a sectional front elevation the section being taken substantially on the line 4-4 of Figure 1.

Figure 5 is a detail of the means to limit the upward and downward movement of the platen carriage.

Figure 6 is a detail front elevation showing the manner of slidably mounting and guiding the carriage support in the frame-

work, the framework being shown in section; and

Figure 7 is a detail plan view to show the manner of locking the levers to shift the platen carriage to maintain the carriage in shifted position.

Similar characters of reference designate like parts throughout the different views of the drawings.

In the embodiment of my invention shown in the drawings the operative parts are carried by a framework, designated in a general way by F, adapted to be supported upon feet 8. A carriage 9 rotatably supports a platen 10 and has a pair of longitudinally extending bars 11, 12 the inner edges of which have longitudinally extending V-shaped grooves 13. The carriage is mounted to have to and fro movement upon a support comprising a rectangular frame 14 having V-shaped grooves 15 in its front and rear edges to constitute with the grooves 13 in the carriage bars 11, 12 raceways for balls 16. Fixed to the opposite ends of the supporting frame 14 are racks 17, 18 slidably engaging in guideways 19 in the framework 80 and guideways 20 in supporting brackets 21 for the feet 8 fixed to the framework, and with which racks pinions 22, 23 mesh, said pinions being fixed to a shaft 24 journaled at its ends in the side members of the framework. Springs 25 connected at one end to the framework, as at 26, and to forwardly extending fingers or hooks 27 secured to the bottom of the carriage supporting racks operating to counterbalance the weight of the 90 platen carriage and its support.

The carriage support is maintained in normal writing position, as shown in Figure 1, by a toothed segment, which is in the nature of a double segment, rotatable with the pinions 22, 23, and shown as comprising a wheel or disk 28 fixed to the shaft 24 adjacent the pinion 22, said wheel having equidistantly spaced pins, shown as three in number, to extend laterally from opposite sides of the wheel, as shown at 29 and 30. In normal writing position of the carriage support the pin at the extreme right of the shaft 24, as viewed from Figure 1, abuts against the top of a tooth 31 at the end of 100 a toothed portion 32 at the right of the wheel 28, as viewed from Figure 4, said toothed portion being formed at the rear

end of a lever 33 pivotally supported, as at 34, in a transverse slot of a cross bar 39 and having a finger key 35 at the forward end. The top of the tooth 31 is in the form of 5 an arc of a circle whose center is in the pivotal support of the lever 33, for a purpose to be hereinafter described. In this position of the carriage support the projecting portion 30 of a pin at the left of the 10 shaft 24 as viewed from Figure 1 also abuts against the top of a tooth 36 of a toothed portion 37 formed at the rear end of a lever 38 and located at the left of the wheel 28 as viewed from Figure 4, said lever being 15 pivotally supported at 40 in a slot of the cross bar 39 and having a finger key 41 at its forward end. The top of this tooth 36 is also in the form of an arc of a circle whose center is in the pivotal support of the 20 lever 38. The levers 33 and 38 are maintained in the Figure 1 position with the ends of the levers forward of the pivots 34, 40 in engagement with a cross bar 42 by springs 43, 44 fixed at one end to a cross bar 45 with 25 the free ends engaging with the levers at the rear of the pivots 34, 40.

To shift the carriage so that the writing position of the platen will be above the normal writing position, or from the position 30 shown in Figure 1 to the position shown in Figure 2, the normal writing position of the platen being shown in dotted lines in this figure, as for instance, to write capital letters or the like, the forward end of the 35 lever 35 is depressed by applying pressure to the finger key 35, as shown in Figure 2, thereby elevating the sector 32, the sector having a slight free movement until the tooth 31 rides off of the pin 29 and the latter is engaged by the next tooth 31' and thereby rotate the wheel 28 in the direction 40 of the arrow (Figure 2) and therewith the shaft 24 and pinions 22, 23, the latter meshing with the racks 17, 18 moving said racks 45 with the frame 14 and platen carriage upward, the upper movement of the carriage support being limited by stops 60, consisting of the laterally bent upper end of a plate 61 secured to the racks 17, 18, engaging 50 with the upper end wall of slots 62 in the side members of the framework, the carriage support being supported during this movement by the engagement of the portion 29 of the pins with the tooth 31', as 55 clearly shown in Figure 2.

To lock the carriage support in its upward shifted position there is provided a slide 47 supported adjacent its opposite ends in the framework, as at 48 and 49, to have a 60 limited rearward and forward movement, the rearward movement being limited by a shoulder 50 engaging with the framework, and the forward movement being limited by a pin 51 engaging with a transverse member 65 at the front of the framework, the slide

being normally maintained in its forward position with the pin 51 engaging with the framework as shown in Figure 1 by a spring 52. When the lever 35 is depressed by moving the slide 47 against the tension of the 70 spring 52, which movement may be imparted to the slide by the thumb of the same hand by a finger of which the lever 33 is depressed, a hook or latch 53 formed on the slide will engage over a pin 54 extending laterally from the lever 33, as shown in dotted lines in Figure 2, the pressure of the 75 spring 43 on the lever at the opposite side of its pivot support retaining the pin in engagement with the latch 53 and the platen 80 carriage supported in elevated position. To release the lever 33 from the slide latch 53 to permit the carriage support to again assume its normal writing position shown in Figure 1, or the platen in the dotted line 85 position shown in Figure 2, pressure is applied to the finger key end of the lever 33 relieving the pressure of the pin 54 on the slide latch 53 when the slide will be returned by the spring 52 to the full line 90 position shown in Figures 1, 2 and 3, and as pressure is released from the finger key 35 the lever 33 will be returned to the Figure 1 position by its spring 43 and thereby 95 the carriage support to the normal writing position as shown in Figure 1.

To shift the carriage support so that the writing position of the platen will be below the normal writing position, or from a position as shown in Figure 1 to the position 100 shown in Figure 3, or from the dotted line position of the platen shown in Figure 3, as, for instance, to write numerals and other characters, the finger key end of the lever 38 is depressed against the action of its 105 spring 44 thereby lifting the toothed lever end 37, said end having a slight free movement until the tooth 36 rides off of the pin 29 and the latter is engaged by the next tooth 36' thereby rotating the wheel 28 in 110 the direction of the arrow indicated in Figure 3, reverse to the movement imparted thereto by the toothed portion 32 of lever 33, and rotate with said wheel the shaft 24 and pinions 22, 23, the latter meshing with 115 the racks 17, 18 moving said racks with the frame 14 and platen carriage downward, the downward movement of the carriage support being limited by the engagement of stops 63, consisting of bending the lower 120 ends of the plates 61 laterally, engaging with the lower end wall of the slots 62 in the side members of the framework, the carriage support being supported during this movement by the engagement of the portions 30 of the pins with the sector 37.

To lock the carriage support in this position with the finger key end of the lever 38 depressed the slide 47 is moved inward thereby causing a latch 57 formed on said 130

slide to engage over a pin 58 extending laterally from the lever 38, said pin being maintained in engagement with said latch through the pressure of the lever spring 44, 5 and thereby locking the carriage support with the platen in the position shown in Figure 3. To release the lever 38 and permit the return of the carriage support to the normal writing position shown in Figure 1, pressure is applied to the finger key 10 end of the lever 38 relieving the pressure of the pin 58 on the slide latch 57 when the slide will again be returned to initial position by the spring 52.

15 Variations may be resorted to within the scope of my invention, and portions of my improvements may be used without others.

Having thus described my invention, I claim:

20 1. In a typewriting machine, the combination with framework, of a platen carriage support including a vertical rack adjacent opposite ends thereof slidably engaging guideways in the framework to have 25 a limited up and down movement; a rotatable shaft; pinions on said shaft to mesh with the racks; and a depressible lever having a finger key at one end and the opposite end arranged to co-operate with means on 30 the shaft to maintain the shaft against rotation and the platen carriage in normal writing position, and adapted to impart rotative movement to the shaft upon the depression of the lever to change the writing 35 position of the platen carriage.

2. In a typewriting machine, the combination with the framework, of a platen carriage support including a rack adjacent opposite ends thereof slidably engaging

40 guideways in the framework to have a limited up and down movement; means including pinions to mesh with the racks operable to impart movement to the racks and carriage support; lever mechanism arranged 45 to co-operate with said latter means to hold the pinions against movement and the carriage support with the platen in normal writing position, and operable to actuate said means to rotate the pinions and thereby 50 shift the carriage with the platen to another writing position for the purpose specified.

3. In a typewriting machine, the combination with the framework, of a platen carriage support including a rack adjacent 55 opposite ends thereof slidably mounted in the framework; pinions to mesh with the racks; lever mechanism arranged to co-operate with means rotatable with the pinions to hold the pinions against rotation and the 60 platen carriage support in normal writing position; and means to co-operate with the lever mechanism to lock the same in position with the carriage support in position with the platen above or below the normal 65 writing position for the purpose specified.

4. In a typewriting machine, the combination with the framework, of a platen carriage support including a rack slidably engaging a guideway in the framework; a pinion to mesh with said rack; a wheel having laterally projecting pins rotatable with the pinion; and a depressible lever having a toothed portion at one end to co-operate with the pin wheel to lock said wheel and pinion against movement and maintain the 70 rack with the platen carriage in normal writing position, and the depression of the end of said lever opposite the toothed portion causing said toothed portion to co-operate with the pins of the wheel to rotate 75 the same and connected pinion to impart movement to the rack to shift the carriage to another writing position for the purpose specified.

5. In a typewriting machine, the combination with the framework, of a platen carriage; a support therefor including a rack engaging in a guideway in the framework to have a limited sliding movement; a pinion to mesh with said rack; a wheel having laterally projecting pins connected to the pinion to rotate therewith; and a depressible lever having a finger key at one end and a toothed portion at the opposite end with which one of the wheel pins co-operates to 90 lock the pinion against movement and maintain the rack with the platen in normal writing position, the depression of the finger key end of the lever causing the toothed portion to co-operate with the wheel pins 95 to rotate the wheel and pinion to impart movement to the rack to shift the position of the carriage, substantially as and for the purpose specified.

6. In a typewriting machine, the combination with the framework, of a platen carriage support including a rack slidably engaging in a guideway in the framework; a pinion to mesh with said rack; a wheel having laterally projecting pins connected to the pinion to rotate therewith; a depressible lever having a finger key at one end and a toothed portion at the opposite end with which one of the wheel pins co-operates to 110 lock the pinion against movement and maintain the rack with the platen carriage in normal writing position, the depression of the finger-key end of the lever causing the toothed portion to co-operate with the wheel pins to rotate the wheel and pinion to impart 115 movement to the rack to shift the position of the carriage; a pin projecting laterally from the lever and a notched slide to co-operate with the lever pin projecting from the lever to lock the lever in depressed position and the carriage in shifted position, substantially as and for the purpose specified.

7. In a typewriting machine, the combination with the framework, of a platen car- 120

riage support including a rack engaging a guideway in the framework to have a limited up and down movement; a pinion to mesh with said rack; a wheel having pins projecting laterally therefrom rotatable with the pinion; a pair of depressible levers each arranged with a toothed end to co-operate with the wheel pins to hold said wheel and pinion against movement and thereby the 10 platen carriage in normal writing position, the depression of one of said levers operating to cause the connected toothed portion to co-operate with the pin wheel to rotate the wheel and pinion in one direction to impart movement to the rack and move the platen above the normal writing position, and the depression of the other lever operating to rotate the wheel and pinion in reverse direction to impart downward movement to the rack and move the platen below the normal writing position for the purpose specified.

8. In a typewriting machine, the combination with the framework, of a platen carriage support including a rack at opposite ends slidably engaging guideways in the framework; pinions to mesh with said racks; a wheel rotatable with the pinions having pins projecting laterally from opposite sides thereof; a pair of depressible levers, each lever having a toothed portion to co-operate with the wheel pins to lock the latter and the pinions against movement and maintain the racks with the platen carriage in 35 normal writing position, the toothed portion of one lever upon the depression of the lever co-operating with the wheel pins to rotate the wheel and pinions in one direction to move the racks and the platen above the 40 normal writing position, and the toothed portion of the other lever upon the depression of said lever co-operating with the wheel pins to rotate the wheel and pinions in reverse direction to move the racks in 45 opposite direction and the platen below the normal writing position; and means to releasably lock either one of said levers in depressed position for the purpose specified.

9. In a typewriting machine, the combination with the framework, of a platen carriage; a support therefor including a rack engaging in a guideway in the framework to have a limited up and down movement; a pinion to mesh with said rack; a wheel 55 to rotate with the pinion; pins extending from opposite sides thereof; a pair of depressible levers, each lever having a finger-key at one end and a toothed portion at the opposite end with which the wheel pins 60 co-operate to lock the pinion and rack against movement with the platen in normal writing position, said toothed portions upon the depression of the levers co-operating with the wheel pins to impart movement 65 to the wheel and pinion and move the rack

and the platen above or below the normal writing position, substantially as and for the purpose specified.

10. In a typewriting machine, the combination with the framework, of a platen 70 carriage; a support therefor including a rack engaging in a guideway in the framework to have a limited up and down movement; a pinion to mesh with said rack; a wheel to rotate with the pinion; pins extending from opposite sides of the wheel; a pair of depressible levers, each lever having a finger-key at one end and a toothed section at the opposite end with which the wheel pins co-operate to lock the pinion 80 and rack against movement with the platen in normal writing position, the depression of one of said levers causing its toothed section to co-operate with the pins at one side of the wheel to rotate the wheel and pinion 85 and impart movement to the rack and move the platen above the normal writing position, and the depression of the other lever causing its toothed section to co-operate with the pins at the opposite side of the 90 wheel to rotate the wheel and pinion in reverse direction and impart downward movement to the rack and move the platen below the normal writing position, substantially as and for the purpose specified. 95

11. In a typewriting machine, the combination with the framework, of a platen carriage; a support therefor including a rack engaging in a guideway in the framework to have a limited up and down movement; a pinion to mesh with said rack; a wheel to rotate with the pinion; pins extending from opposite sides thereof; a pair of depressible levers, each lever having a finger-key at one end and a toothed portion at the opposite end with which the wheel pins co-operate to lock the pinion and rack against movement with the platen in normal writing position, said toothed portions upon the depression of the finger-key end of the levers co-operating with the wheel pins to impart movement to the wheel and pinion and move the rack and the platen above or below the normal writing position; pins projecting laterally from 115 the levers, and a notched slide to co-operate with lever pins to lock either of said levers in depressed position with the rack raised or lowered and the platen either above or below the normal writing position, substantially as and for the purpose specified. 120

12. In a typewriting machine, the combination with the framework, of a platen carriage; a support therefor including a 125 rack engaging in a guideway in the framework to have a limited up and down movement; a pinion to mesh with said rack; a wheel to rotate with the pinion; pins extending from opposite sides of the wheel; 130

a pair of depressible levers, each lever having a finger-key at one end and a toothed portion at the opposite end with which the wheel pins co-operate to lock the pinion and 5 rack against movement with the platen in normal writing position, the depression of one of said levers causing the toothed portion thereof to co-operate with the pins at one side of the wheel to rotate the wheel 10 and pinion and impart movement to the rack and move the platen above the normal writing position, and the depression of the other lever causing its toothed portion to co-operate with the pins at the opposite 15 side of the wheel to rotate the wheel and pinion in reverse direction and impart downward movement to the rack and move

the platen below the normal writing position; pins projecting laterally from the levers; and a spring influenced slide having 20 a pair of notches to co-operate with pins extending from the levers to lock either of the levers in depressed position with the rack raised or lowered and the platen either above or below the normal writing 25 position; said slide being releasable from the lever pins through the influence of its spring by depressing the levers, substantially as and for the purpose specified.

Signed at New York city, in the county 30 of New York and State of New York this 9th day of June 1917.

RICHARD W. UHLIG.
